(57) **CLAIM**

The ornamental design for a noise suppression building, as shown and described.

DESCRIPTION

FIG. 1 is a front elevational view of a noise suppression building illustrating the present design;

FIG. 2 is a left side elevational view of the noise suppression building shown in FIG. 1;

FIG. 3 is a rear elevational view of the noise suppression building shown in FIG. 1;

FIG. 4 is a right side elevational view of the noise suppression building shown in FIG. 1;

FIG. 5 is a top plan view of the noise suppression building shown in FIG. 1;

FIG. 6 is a bottom plan view of the noise suppression building shown in FIG. 1;

FIG. 7 is another bottom plan view of the noise suppression building shown in FIG. 1, shown in an alternate environment without the unclaimed structure shown in FIG. 6;

FIG. 8 is a front isometric view of the noise suppression building shown in FIG. 1;

FIG. 9 is a rear isometric view of the noise suppression building shown in FIG. 1; and,

FIG. 10 is a front isometric view of the noise suppression building shown in FIG. 1 in a typical environment with a muffler.

The broken line showing in FIGS. 6, 7, and 10 is for environmental purposes only and forms no part of the claimed design.
